[57] ABSTRACT

An apparatus for wipe cleaning the extrusion face of a spinneret that includes a post mounted in the center of the spinneret normal to its extrusion face with a bushing mounted to the post for movement toward and away from the extrusion face and for rotary movement about the post. An arm is attached to the bushing and extends outwardly from the bushing toward the orifices. A blade is attached to the arm and the blade has an edge parallel to the extrusion face of the spinneret of sufficient width to encompass the spinneret orifice area in one revolution of the blade around the post.

FIG. I

FIG. 2

FIG. 3

SPINNERET WIPER

BACKGROUND OF THE INVENTION

This invention relates to a device for cleaning the extrusion face of a spinneret.

In the conventional melt spinning of synthetic fibers from thermoplastic polymers, the polymeric materials after being heated to a plastic, flowable state are forced under pressure through minute holes formed in the face of a spinneret plate to form filamentary structures which after suitable treatment such as cooling and stretching are wound onto packages or formed into tows for further processing into filaments or yarns suitable for use in various textile articles. During the extrusion process, deposits of decomposed polymeric materials and/or various polymeric ingredients form around the extrusion orifices in the spinneret. Periodically, this accumulation of deposits is removed by wiping or scraping the face of the spinneret plate with a tool generally referred to as a wipe stick. In the course of such wiping, the spinneret orifices are subject to damage from the ends of the wipe stick blade. Variations in wiping technique among operating personnel also lead to differences in the uniformity and completeness of the wiping operation. Subsequent spinning performance is affected to a large degree depending on the skill of the particular operator to wipe cleanly and without damaging the orifices. Conventional apparatus for wiping spinnerets is a hand held wipe stick operated free-hand.

SUMMARY OF THE INVENTION

An apparatus for wipe cleaning the extrusion face of a spinneret attached to a spinning pack assembly by a plurality of bolts including one center mounting bolt, said spinneret having a plurality of spinning orifices arranged around said center mounting bolt, said apparatus comprising: a post for mounting in place of said center mounting bolt; a rotatable bushing slidably mounted on said center post for movement toward and away from said extrusion face and rotary movement around said post; an arm attached to and extending outwardly from said bushing toward said orifices; and a blade attached to said arm, said blade having an edge parallel to said extrusion face, the movement of said bushing toward said extrusion face being sufficient to permit said edge to engage said extrusion face. The edge of said blade has sufficient width to encompass the spinneret orifice area in one revolution of said blade around said post.

BRIEF DESCRIPTION OF THE DRAWING

FIG. 1 is a side view partly in section of the novel spinneret wiper shown in association with a spinneret.

FIG. 2 is a perspective view showing the wiper in use during a wipe cycle, and

FIG. 3 is a plan view showing another wipe path that may be made with the invention.

DETAILED DESCRIPTION OF A PREFERRED EMBODIMENT

In FIG. 1, there is shown a part of a standard melt spinning spinneret 10 which is normally a steel plate of sufficient thickness to withstand the extrusion pressures associated with melt spinning of synthetic fila-

ments. Molten polymer is forced under pressure by means not shown through the spinneret orifices 16. The spinneret is bolted by suitable means such as mounting bolts 12 to the spinneret block of a melt spinning machine not shown. In the preferred embodiment of the invention, when the spinneret is to be wiped, the center mounting bolt of the spinneret is removed after the flow of molten polymer is stopped and the hex head bolt 13 is screwed into the center threaded section of the pack cavity vacated by the mounting bolt. The shoulder 15 of the hex head bolt 13 is turned up tight to the bottom surface or extrusion face of the spinneret 10. The wiper assembly comprising rotatable bushing 20 slipped onto center post 18 and carrying horizontal arm 22 and wiper blade 30 in handle 28 is then fixed to the spinneret by screwing the center post into the threaded head section of the hex head bolt 13. The position of the wiper blade 30 fixed to handle 28 which is slidably mounted in collar 27, may be adjusted then locked in the desired location by means of the set screw 26 in the collar. The length selected in the design of horizontal arm 22 is determined by the location of the holes in the spinneret face. The width of the wiping edge 31 of blade 30 is selected to extend the edge beyond the innermost and outermost row of holes in the circular hole pattern and the blade face is mounted essentially on a radial line from the center of the mounting post 18. The assembly maintains the blade edge parallel to the spinneret face and permits guiding the blade in a circular pattern such that the blade ends are always outside of the spinneret orifice area.

In operation, after attachment of the wiper to the spinneret, wiping is accomplished as shown in FIG. 2 by the operator who grasps handle 28 and slides the rotatable bushing 20 up center post 18 so that the blade contacts the spinneret face, and then in a circular motion whose path is determined by the assembly, completes the circuit of the blade in contact with the face a minimum of once around the spinneret, ending with contact smoothly released and the blade away from the spinneret face. The bushing 20, preferably a ball bushing, permits both vertical movement toward and away from the extrusion face of the spinneret 10 and rotary movement around post 18 of the wiper. Vertical movement is necessary to permit ending the wipe with the blade off the spinneret surface. In its rotary movement, the blade is guided in a fixed circle matched to the spinneret hole pattern by the length of the horizontal arm 22.

The wiper may be used to wipe any spinneret that permits location of a pivot point. FIG. 3 illustrates the wipe path of a blade rotated about a pivot point 34 located outside the periphery 36 of the hole pattern area of a spinneret face. In this embodiment, the center post may be mounted with a hex head bolt 13 fitted to a part of the spinning machine (not shown), or by replacement of a mounting bolt 12 supporting the spinneret periphery by the hex head bolt 13. Blade width and sweep arc 40 are selected so that the wiping area of the blade encompasses the hole area of the spinneret as illustrated. Starting and finishing positions of blade 30 and the outline (broken lines) of its arcuate path during a wipe are shown.

The mechanical wiper of this invention, eliminates damage to the orifices from scratches caused by the ends of the wiper blade. These scratches are common with hand guided wiping. The repair of orifices dam-

aged by these scratches entails considerable labor by skilled operators. If damage is severe, the spinnerets must be discarded. Spinneret wiping with the mechanical wiper of this invention, prolongs spinneret operating time before a spinning pack change is necessary. In addition, improved spinning continuity and product yield are realized when the wiping means of this invention is used because more even contact pressure may be maintained and more uniform and complete wiping is achieved.

What is claimed is:

1. An apparatus for wipe cleaning the extrusion face of a spinneret attached to a spinning pack assembly by a plurality of bolts including one center mounting bolt, said spinneret having a plurality of spinning orifices arranged around said center mounting bolt, said apparatus

tus comprising: a post for mounting in place of said center mounting bolt; a rotatable bushing slidably mounted on said post for movement toward and away from said extrusion face and for rotating movement around said post; an arm attached to and extending outwardly from said bushing toward said orifices; and a blade attached to said arm, said blade having an edge parallel to said extrusion face, the movement of said bushing toward said extrusion face being sufficient to permit said edge to engage said extrusion face.

2. The apparatus as defined in claim 1, the edge of said blade having sufficient width to encompass the spinneret orifice area in one revolution of said blade around said post.
